UNITED STATES PATENT OFFICE.

WILLIAM M. DUCKER, OF NEW YORK, N. Y.

HINGE.

SPECIFICATION forming part of Letters Patent No. 308,883, dated December 9, 1884.

Application filed December 8, 1883. (No model.)

To all whom it may concern:

Be it known that I, WILLIAM M. DUCKER, a citizen of the United States, residing in the city of New York, in the county of New York 5 and State of New York, have invented certain new and useful Improvements in Hinges; and I do hereby declare the following to be a full, clear, and exact description of the invention, which will enable others skilled in the art to which it appertains to make and use the same, reference being had to the accompanying drawings, which form a part of this specification, and in which—

Figure 1 is a view of the back of a box with the cover attached by my hinge. Fig. 2 is a cut section of Fig. 1, showing the hinge inserted into the wood. Fig. 3 is a cut section of a box similar to Fig. 1, showing another method of applying my hinge. Fig. 4 is a side view of the hinge with the staples in place, and showing one form of teeth. Fig. 5 is a top view of Fig. 4. Fig. 6 is an end view of Fig. 4, and shows the staple made with barbs. Fig. 7 is a side view of a hinge, showing another form of teeth. Fig. 8 is an end view of one of the teeth of Fig. 7, showing the same barbed. Fig. 9 is a side view of a hinge adapted to be secured by a screw. Fig. 10 is a top view of Fig. 9. Fig. 11 is an end view of Fig. 9. Fig. 12 is a portion of a piano-top, showing the swinging lid Z attached by the hinge Fig. 9.

Similar letters of reference indicate like parts in all the drawings.

In making my hinge, two blanks or arms, *a a*, which may be alike, are cut or stamped, preferably from a sheet of metal, to form a rectangular shape, having at one side or corner suitable projections to form the ears *b*, 35 through which they are united parallel-wise by the pintle *c*. To attach this hinge to the box or structure all that is necessary is to make a cut therein of the depth of the arms *a a*, and a small recess, to allow movement to 40 the pintle, and then insert the hinge edgewise into these cuts, as shown in Figs. 2 and 3.

I show a number of means to secure the hinge in position after it is inserted in place. One is to cut a notch or slot, *d*, on the upper 45 edge, and drive a staple, *e*, down to fit in this notch. For many uses the ordinary double-

pointed tack will be a sufficient holding device, especially when used in connection with the teeth or projections hereinafter mentioned; or the shanks of the tack or staple may be provided with barbs or corrugations; as indicated in Fig. 6, or a larger or stronger staple with or without barbs or corrugations may be employed, depending upon the strength required in any particular application of the hinge. 55 The attachment of the arms is still further secured or strengthened by extending from their lower edge the teeth or pins *f* or *f'*, which are driven into the wood, and which may likewise have corrugations or barbs, as indicated in Fig. 8; or they may have swelled-out portions, as shown in Fig. 7, or have both the swelled-out parts and the barbs, to secure a firm and rigid connection.

In that form of my hinge provided with the pins *f' f'*, having swelled-out parts, there is an enlargement of the pin between the arm *a* and the point of the pin. When two such pins are used, the enlarged parts may be toward each other, as shown in Fig. 7, and when these 75 are driven into the wood the effect is to compress the wood between the pins *f' f'* while they are driven home, and then the wood expands into the enlarged space above and between the swelled-out parts of those pins, 80 thereby making a very firm and strong attachment.

Another method of securing the hinge, and the one which I consider the best for use on piano-covers, is that shown in Figs. 9 to 12. 85 In this slits are made in the blanks or arms *a a*, and the parts *g h i* are forced out sidewise, leaving an opening for the stem of the screw, the upper edge being also rounded out to receive the head of the screw. In this method of securing the hinge the pins or teeth *f'* may also be employed in addition to the screw; but I deem the screw sufficient. These arms *a a* are inserted in place in the same manner as those already described; but in addition to the cut a suitable opening should be provided to receive the swelled-out parts *g h i*, through which the screw passes to secure the arms in place. These hinges are adapted to be used especially on pianos or 95 other structures where hinges are desirable 100 which do not expose much metal surface to

view; and they may be driven down below the adjoining surfaces and readily covered over, to be still more concealed; but they may also be used for any purpose where a simple and 5 strong hinge is required.

This construction of hinge has many advantages over hinges heretofore known. It requires very little metal or work to make it, and it can be easily attached. The arms can 10 be made as long as the width of the material of the box or structure, so that in a box of half-inch stuff each arm can be half an inch long and extend clear across the material, thus giving a brace against lateral motion of the 15 full strength of the material. The holding device employed gives a firm and rigid attachment, and when the teeth or pins are used the cut in the stuff acts as a guide for driving them into the proper place. It possesses the full 20 strength of a mortise-hinge containing an equal amount of material, and requires a great deal less labor and skill to attach it. It is as cheap as or cheaper than the ordinary leaf-hinge, and attached about as easily as such a hinge.

25 These hinges can be stamped or cut out from sheet metal. They are exceedingly simple and cheap in construction, very strong and firm in holding-power, and can be easily applied.

I am aware of Letters Patent Nos. 181,843 and 238,320, describing hinges provided with 30 shanks or teeth, and hinge-connections bent at right angles thereto, and to be attached without screws or nails.

I am aware of the patent to H. E. Griffin, dated December 10, 1878, and bearing No. 35 210,686; but I do not claim any of the matter therein shown and described.

What I do claim is—

1. In a hinge, the arms *a* and pintle *c*, uniting the same at right angles to their plane of 40 movement, in combination with a staple, *e*, for securing said arms to their respective hinged parts.

2. In a hinge, the arms *a*, acting in parallel planes, and having ears *b*, notches *d*, for 45 the purpose described, and drive-spurs, in combination with the staple *e*, for securing said arms to their respective hinged parts.

3. In a hinge, the arms *a*, carrying drive-spurs, said spurs having an enlargement mid- 50 way of their length, for the purpose set forth.

WILLIAM M. DUCKER.
